UNITED STATES PATENT OFFICE.

GREGOR W. GILL, OF MANOKIN, MARYLAND.

DESIGN FOR A LATHER-RUBBER.

44,872.

Specification for Design.

Patented Nov. 11, 1913.

Application filed June 19, 1913. Serial No. 774,693. Term of patent 14 years.

To all whom it may concern:

Be it known that I, GREGOR W. GILL, a citizen of the United States, residing at Manokin, in the county of Somerset and State of Maryland, have invented a new, original, and ornamental Design for a Lather-Rubber, of which the following is a specification, reference being had to the accompanying drawing, forming part thereof.

Figure 1 is a perspective view of a lather

rubber, showing my new design. Fig. 2 is a side elevational view of what is shown in Fig. 1.

I claim:

The ornamental design for a lather rubber, as shown.

GREGOR W. GILL.
